UNITED STATES PATENT OFFICE.

JAMES L. HIATT, OF SAPULPA, OKLAHOMA, ASSIGNOR TO SCHRAM GLASS MANUFACTURING COMPANY, OF ST. LOUIS, MISSOURI, A CORPORATION OF MISSOURI.

CONVEYER.

1,334,453.

Specification of Letters Patent. Patented Mar. 23, 1920.

Application filed September 30, 1918, Serial No. 256,198. Renewed August 9, 1919. Serial No. 316,489.

To all whom it may concern:

Be it known that I, JAMES L. HIATT, a citizen of the United States, and resident of Sapulpa, Oklahoma, have invented certain new and useful Improvements in Conveyers, of which the following is a specification containing a full, clear, and exact description, reference being had to the accompanying drawings, forming a part hereof.

10 My invention relates to conveyers and has for its object a conveyer by which molded articles of glass are conveyed from a molding machine into a leer or annealing furnace. A further object is to provide a conveyer whereby the molded articles of glass are conveyed from the molding machine in a single file, thence on to the revolving disk receiver and from there discharged on to the leer pans.

20 In the drawings,

Figure 1 is a top plan view of my device with parts broken away.

Fig. 2 is a side elevation of the same with parts broken away.

25 Fig. 3 is an enlarged rear view of a portion of my device with parts in section, taken on line 3-3 of Fig. 1 and looking in the direction of the arrow.

Fig. 4 is a view of the same taken on the line 4-4 of Fig. 3 and viewed in the direction of the arrow.

30 Fig. 5 is a bottom plan view of the removing mechanism made use of, showing the revolving disk receiver in dotted lines, and taken on the line 5-5 of Fig. 3, and viewed in the direction of the arrow, and

Fig. 6 is a fragmental view showing the conveyer and the revolving disk receiver together with the guide bar, taken on the line 40 6-6 of Fig. 4 and viewed in the direction of the arrow.

In carrying out my invention, I provide a frame 6 which is located in front of the leer or annealing furnace 7. The frame 6 is composed of uprights 8 and guide bars 9 and 10. The portion of the upright 8 next the leer 7 is provided with an upwardly extending projection 11, and cross bars 12 and 13. These cross bars 12 and 13 are 45 provided with journals 14, 15, 16 and 17. In the journals 14 and 15 is located a vertical shaft 18, provided at its upper end with

50 a set collar 19 and at its lower end with a revolving disk receiver 20. This revolving disk receiver 20 is provided with a flanged hub 21, which is secured to the plate by means of rivets or similar binding devices 22 and secured to the shaft 18 by means of a set screw 23. Immediately below the journal 15 and rigidly secured to the shaft 18 55 is a gear 24 and between the gear 24 and the flanged hub 21 is located a sleeve 25 on which a discharger 26 is rigidly secured. Meshing with the gear 24 is a gear 27 which is located on the shaft 28, this shaft being 60 mounted in the journals 16 and 17 and is provided at its upper end with a bevel gear 29, which gear meshes with a similar gear 30. The gear 30 is mounted on the horizontal shaft 31 which is directly connected 65 to a motor or other suitable source of energy 35, and this shaft is provided at its outer end with the pulley 32.

In the frame 8 is located a shaft 34 on which is mounted a pulley 36. A belt 37 70 transmits the power from the pulley 32 to the pulley 36, placing the conveyer in operation. Attached to the shaft 34 is a pulley 41 around which a conveyer belt 42 is placed, this belt also passing around an idle 75 pulley 43, which is located at the rear or feeding end of my device.

The discharger 26 consists of an arm 44, having a rectangular block 45 at its one end, in which is formed the semi-circular 80 depression 46, which fits around the sleeve 25. Another block 47 provided with a similar semi-circular depression 48 completes the circle and when these blocks are clamped together by means of the screws 49, the discharger is securely bound to the sleeve 25. The arm 44 of the discharger is provided with a bent bar 50, which is adapted to contact with the glass articles and discharge 85 them from the disk 20 on to the leer pans 40. 90

The guide bar 9 is provided at its end nearest the leer with a curved portion 51, the object of which is to direct the glass articles upon the revolving disk receiver 20. The shaft 28 is provided at its lower end 100 with a disk 52, to which is connected a lever 53, this link having its one end 54 pivotally secured to the portion 45 and its end 55 being slotted as indicated by the nu-

meral 56. Through this slotted portion extends the stud 57 so that when the disk 52 is revolving the discharger is operating.

The operation of my device is as follows:

- 5 The glass articles having been molded are taken from the molding machine in the usual manner and placed upon the conveyer 42. In referring to Figs. 1 and 2 it will be seen that these articles are spaced quite a 10 distance apart, traveling on the conveyer 42 until they come in contact with the curved portion 51 of the bar and which places them on to the revolving disk receiver 20. This revolving disk receiver 20 revolving slower 15 or at a less lineal speed than the conveyer 42 will allow the glass articles to assemble closely thereon and when that portion of the plate 20 which corresponds to the width of the leer pans is filled, the discharger 26 20 is operated, pushing the glass articles off on to the leer pans as shown in Fig. 1.

The discharger then moves back to its original or starting position in advance of the new batch of glassware being fed on to 25 the disk 20 and then the operation is repeated. By means of the slot 56, the discharger is halted temporarily at each point when the stud 57 is passing the dead center.

By the use of my device I find that it is 30 possible to save man-power and time in making glass articles, as the same have to be annealed after coming from the molding machine. The different glass articles are placed directly on the conveyer and from 35 there mechanically fed into the leer or annealing furnace without first passing on a table or any receptacles and then re-discharging them in to the leer to be annealed.

- 40 From the foregoing it will be seen that the discharger 26 is positively and periodically operated in opposition to the rotation of the revolving disk receiver 20, and by adjusting the stud 57 closer to the center of the disk 52, 45 the sweep of the discharger 26 may be regulated. The holes 58 in the disk 52 being provided for such an adjustment if desired.

By means of the longitudinal conveyer 42 and the revolving disk receiver 20, the glass 50 articles may be conveyed direct from the mold or forming machine on to the leer pans.

The bent bar 50 is so constructed that it 55 may be bent in or out corresponding to the size of articles to be discharged, also to regulate its angle to the arm 44.

What I claim is:

1. A conveyer comprising a longitudinal conveyer, leer pans, a revolving disk receiver interposed between the conveyer and leer 60 pans, means for removing the articles from the revolving disk receiver to the leer pans, and means for operating the conveyer.
2. A conveyer comprising a frame, a longitudinal conveyer mounted in the frame, a revolving disk receiver mounted in the 65

frame, a discharger mounted in the frame and above the revolving disk receiver, and means for placing the conveyer in operation.

3. A conveyer comprising a frame, a longitudinal conveyer mounted within the frame, leer pans mounted without the frame, a revolving disk receiver mounted within the frame, its periphery running level with the longitudinal conveyer, a discharger located in the frame and above the revolving disk receiver, means for operating the discharger, means for operating the conveyer and gathering disk and means for operating the leer pans.

4. A conveyer comprising a frame, a longitudinal conveyer mounted in the frame, a revolving disk receiver mounted in the frame, a discharger mounted in the frame and above the revolving disk receiver, a leer bed mounted next the discharge end of the revolving disk receiver and means for placing the longitudinal conveyer and revolving disk receiver in operation simultaneously.

5. A conveyer comprising a frame, a longitudinal conveyer mounted in the frame, a revolving disk receiver mounted in the frame and having its periphery running level with the longitudinal conveyer, a discharger mounted in the frame and above the disk receiver for pushing the articles from the disk receiver, a leer extending beyond the discharge end of the disk receiver, leer pans extending under the disk receiver and adapted to receive articles discharged from the disk receiver, and means for placing the several movable parts of the conveyer in operation.

6. A conveyer comprising a support, a longitudinal conveyer mounted on said support, a revolving disk receiver mounted at one end of the longitudinal conveyer and adapted to receive articles discharged from said longitudinal conveyer, a guide for directing the articles from the longitudinal conveyer to the receiver, a horizontally sweeping discharger mounted above the revolving disk receiver and adapted to move in a direction opposite to the rotation of the receiver for discharging articles therefrom.

7. A conveyer comprising a support, a longitudinal conveyer mounted on said support, a revolving disk receiver mounted at one end of the longitudinal conveyer and adapted to receive articles discharged from said longitudinal conveyer, a horizontally sweeping discharger mounted above the revolving disk receiver and adapted to move in a direction opposite to the rotation of the receiver for discharging articles therefrom.

8. A conveyer comprising a support, a longitudinal conveyer mounted on said support, a revolving disk receiver having a linear speed less than the linear speed of the longitudinal conveyer and mounted to one

1,834,458

3

side and near one end of the longitudinal
conveyer and adapted to receive articles dis-
charged from the longitudinal conveyer, a
horizontally sweeping and intermittently
5 moving discharger mounted above the re-
ceiver and adapted to move in a direction
opposite to the rotation of the receiver for
discharging articles therefrom.

In testimony whereof, I have signed my
name to this specification, in presence of 10
two subscribing witnesses.

JAMES L. HIATT.
